STEERING BABY CARRIAGE

Harold F. Shaw, Leominster, Mass., assignor to
 F. A. Whitney Carriage Company, Leominster,
 Mass., a corporation of Massachusetts

Application January 23, 1945, Serial No. 574,123

5 Claims. (Cl. 280—48)

1

This invention relates to steering baby carriages and the object of the invention is to provide improvements in the construction of such a carriage contributing to the comfort and safety of the baby and to the convenience of the nurse, as will more fully appear from the detailed description of the illustrative embodiment shown by way of example in the accompanying drawing, wherein—

Fig. 1 is a perspective view of the carriage, the upper portion of the pusher bar being broken away;

Fig. 2 is a bottom plan of the running gear of the carriage, the body being omitted; and

Fig. 3 is a view similar to Fig. 2 showing the parts in another position.

The body is in collapsed position in Figs. 2 and 3.

Referring to the drawing, the carriage there shown comprises a body 10 conveniently of the collapsible type supported substantially centrally thereof and at either side from the end portions of a cross-member 12 to which are joined by vertical pivots 14 two non-parallel longitudinal reaches 16, the ends of which are connected by vertical pivots 18 to front and rear non-rotatable, wheeled axles 20. Herein the reaches incline inwardly from rear to front, forming with the intervening segments of the axles an isosceles trapezoid when the parts are centralized and the carriage is pointed straight ahead. With this arrangement of parts, if, for example, a lateral force is applied toward the left on the cross-member 12, the axles will be turned in a direction to make a turn to the right. The construction as so far described is not novel to the present application.

The body 10 is here shown as of known construction, being in effect a flexible basket or bag capable of collapsing and supported from its upper periphery by the X-shaped frame elements on either side. The frame at each side comprises a long link 22, herein shown (Fig. 1) extending diagonally upwardly and rearwardly from the front and pivotally connected at its upper end to the body. A shorter link 24 extends on the opposite diagonal and is jointed at 26 to the link at the cross of the X. This link forms one element of a toggle, the other element 28 of which is pivoted to the end of the link and at 30 to the upper edge of the body. Element 28 is formed as usual by the lower portion of the side of the pusher bar (the upper portion being omitted in Fig. 1 and concealed by the body in Figs. 2 and 3 because folded over the same in the folded position of the carriage there shown). A latch 32 locks together the parts 24 and 28 as a rigid unit when the carriage is in the erected position of Fig. 1. The

2

lower ends of the crossed elements 22 and 24 are suspended from the cross-member 12 by longitudinal springs 34 secured centrally to the latter, as by the rivets 36 through the extremities of the cross-member and the central portions of inwardly facing arcuate bracing elements 38, the outer ends of which are rigidly secured to the springs and which are centrally traversed by the pivots 14. The springs 34 are concaved upwardly and provided with inturned C-shaped or scrolled ends.

To utilize the very soft cushioning action possible with such springs while providing that a guiding force exerted on the handle carried by the body proper, herein as a part of the collapsible supporting frame described, will be effective to transmit a turn-initiating movement to the cross-member 12, the lower end of the frame elements 22 and 24 and the ends of the springs are connected by straps 40 adapted to swing on the connected parts, these straps herein being in the nature of links turning on horizontal pivots. Effective steering action may thus be obtained by traction exerted through the straps, yet the carriage is manipulated by the cushioned body and no shocks are transmitted from the running gear to the hands.

To provide for braking the carriage, although the body springs freely and in steering turns relatively to the axles, a brake bar 42 is provided having ends opposing a pair of the wheels and supported by vertical pivots on the ends of bracket-like elements 46 projecting substantially rigidly from the rear axle 20, the brake bar consequently being held in fixed angular relation to the rear wheels independently of movement of the body. The bar may be flexed by pressing the central portion thereof away from the axle to throw the outer end into braking contact with the wheels, as by means of the mechanism shown, which is the same as that described in the patent to Potter 1,281,415, October 15, 1918, and which therefore requires no detailed description in the present place.

To limit the swinging movement of the reaches and therefore the angular movement of the axles, U-shaped members 48 (best seen in Fig. 1) may be provided disposed at the side of the cross-member 12 opposite the reaches. The central portion of these straps may be traversed by the pivots 14, thus aiding providing a long bearing for the latter. In Fig. 1 will be seen a washer 50 surrounding pivot 14 and disposed between elements 48 and the overlying braces 38. Thus in the example shown the length of the pivot is from the lower face of the reach to the upper face of the brace 38. The legs of the U-shaped ele-

ments are secured to the reaches at opposite sides of the cross-member 12, their spacing being somewhat greater than the width of that member but such that they will engage the cross-member and stop further movement about the pivots 14 when the parts are in predetermined extreme positions in either direction. Shearing strain on the rivets is minimized by this construction.

Yieldable means may be provided for normally centralizing the linkwork which permits the steering of the carriage which will then normally be in a condition of adjustment for straight-ahead movement. Herein there is shown a pair of helical extension springs 52 located beneath the body in the space between the reaches 16. Each spring is connected at one end to a reach and extends diagonally and is anchored at the other end to a part which moves angularly relative to the reach in the steering movement of the carriage, herein to the central portion of the cross member 12. This construction is simple and rugged and effective for its purpose without offering undesirable resistance to the steering manipulation of the vehicle. It is out of the way where it cannot foul the baby's blankets when they are being put into or taken out of the body and cannot catch the skirt or snag the stockings of the nurse. It is inconspicuous, indeed in effect invisible, so that the attractive appearance of the carriage is not altered thereby.

Under some circumstances it may be desirable to lock the running gear of the vehicle to the position of Fig. 2 for straight-ahead running. For this purpose there is provided a bar 54 which is shown in Figs. 2 and 3 in an intermediate position for purposes of disclosure. It is pivoted on the left-hand end, viewing those figures, to the left-hand reach 16, herein and conveniently on the stud which secures thereto the left-hand spring 34. When the carriage is used as a steering carriage it could be swung out of the way into line with the reach. If it is desired to lock the carriage, the right-hand end thereof may be engaged with the cross-member 12 at the point 56 and will define with the portion of the left-hand reach 16 extending in Fig. 2 upwardly from pivot 14 and the intervening segment of that member between 14 and 56 an indeformable triangle which will lock the running gear with the axles in the parallel position shown in Fig. 2.

It will be apparent that the invention may be embodied in other specific forms without departing from the spirit or essential attributes thereof, and the present embodiment should therefore be considered in all respects as illustrative and not restrictive, as is in fact clear in several matters from the description itself. Reference is to be had to the appended claims to indicate those principles of the invention exemplified by the particular embodiment described and which it is desired to secure by Letters Patent.

I claim:

1. A baby carriage comprising front and rear non-rotatable wheeled axles, a pair of non-parallel longitudinal reaches secured at their ends to said axles by vertical pivots spaced from the centers of the axles; the reaches presenting at a location between the axles bearing portions at opposite sides of the center line of the carriage, a pair of longitudinal springs having scrolled ends, the springs being centrally supported at said location from the reaches by means permitting turning movement about vertical pivots of said reaches relative thereto, a body received be-

tween the springs, a handle carried by the body for trundling the carriage, the body being suspended from the ends of the springs by straps swingable on the connected parts, whereby the body may freely cushion on the springs but turning force exerted on the body by said handle will be exerted through the straps differentially to turn the reaches and turn at least one of the axles to steer the carriage.

2. A baby carriage comprising a pair of wheeled axles, underframe elements connecting the same and joined to said axles by vertical pivots permitting the axles to assume different angles to one another and to said elements as the carriage is guided in different directions, springs rising from the underframe, a body suspended by the springs, a pair of arms projecting from an axle, a brake bar supported therefrom having end portions serving as shoes presented to the wheels in fixed relation to the center thereof independently of movement of other parts of the carriage relative to the axle and means between axle and bar for controlling the application and release of the brake.

3. A steerable baby carriage comprising a body, a substantially centrally located transverse element from which the body is supported, a pair of non-parallel longitudinal reaches terminally pivoted on vertical pivots to front and rear non-rotatable wheeled axles, the reaches crossing said element and pivoted thereto, and U-shaped straps overlying the other side of said element and having their legs secured to the reaches, the legs engaging said element to limit swinging movement of the reaches relative thereto.

4. A steerable baby carriage comprising a body, a substantially centrally located transverse element from which the body is supported, a pair of non-parallel longitudinal reaches terminally pivoted on vertical pivots to front and rear non-rotatable wheeled axles, the reaches crossing said element, U-shaped straps overlying the other side of said element and having their legs secured to the reaches, and vertical pins traversing the central portions of said straps, the reaches and said element to pivotally connect the reaches and element, the legs engaging said element to limit swinging movement of the reaches relative thereto.

5. A baby carriage comprising front and rear non-rotatable wheeled axles, a pair of non-parallel reaches secured at their ends to said axles by vertical pivots spaced from the centers of the axles, a cross-member parallel to the axles between the same pivoted to the reaches by vertical pivots and having ends extending outwardly beyond the same, lateral elements secured substantially centrally thereof to said ends, braces secured to the lateral elements remote from said ends and traversed by the adjacent pivots connecting the cross-member to the reaches, and a body supported from said lateral elements.
